UNITED STATES PATENT OFFICE.

JOHN W. SEIFERT, OF EAST POINT, GEORGIA.

BOILER WASHING-MACHINE.

No. 880,334.

Specification of Letters Patent.

Patented Feb. 25, 1903.

Application filed July 17, 1907. Serial No. 334,204.

To all whom it may concern:

Be it known that I, JOHN W. SEIFERT, a citizen of the United States, and a resident of East Point, in the county of Fulton and 5 State of Georgia, have invented an Improved Boiler Washing-Machine, of which the following is a specification.

My present invention is an improvement upon the boiler washing-machine for which 10 I have received Letters Patent No. 850,061, dated Apr. 9, 1907.

The features embodying the invention are hereinafter described, and illustrated in the accompanying drawings, in which

15 Figure 1 is a side view of the machine. Fig. 2 is a front view of the same. Fig. 3 is a vertical section on the line 3—3 of Fig. 2, the top of the body or casing being closed. Fig. 4 is a central vertical section parallel to 20 the plane of the section shown in Fig. 3, the cover being detached and the clothes-drum shown in elevated position. Fig. 5 is a horizontal section taken through the top portion of the machine, on line 5—5 of Fig. 1. Fig. 25 6 is a detail view illustrating the spring fastenings for holding the door of the clothes-drum closed.

The body A of the machine is constructed of sheet metal, and preferably rectangular in 30 form. Within said body is arranged a fuel grate a, and below it an ash-pan a', a smoke-hole and collar being provided at a point above the grate. The body A is provided exteriorly with handles for convenience in 35 lifting or transporting it. A water-holder, or kettle, B, is supported upon the top edge of the body A and provided with a pipe b, see Fig. 5, which extends through the side of the body and is there provided with a discharge cock b'. The bottom of the kettle is 40 semicircular and the sides are straight, as will be understood by reference to Figs. 4 and 5. The top or cover A' of the body A is hinged to the latter at a² and may be turned 45 over to the front to the position indicated by dotted lines, Fig. 4, in which position it is self-supporting and is thus adapted to serve as a receptacle for the clothes discharged from the clothes-drum C, when the latter is 50 raised to the position indicated by full lines Fig. 4. In such case the door C' of the drum being opened it projects down into the inverted cover A'. The rear curved side of the cover A' is provided with a handle for 55 convenience in manipulating it. The hinges a², see Fig. 2, are of the socket type; the

pintles of the two hinges pointing in the same direction, which adapts the cover A' to be detached from the body A by sliding the former laterally far enough to remove the 60 pintles from the sockets. A clothes-drum C is provided with journals c, c', which support the drum in normal position within the kettle B, as shown in Fig. 3. One of these journals c is squared at the end to adapt it 65 for attachment of a crank c² for rotating the drum. The periphery of the latter is constructed of woven wire, corrugated as shown. The heads of the drum are conical and provided with perforations to admit water, and 70 the inner ends of the journals c, c', are enlarged and made concavo-convex to adapt them to fit upon the drum heads, as shown in Fig. 5.

In place of the means exhibited in my 75 aforesaid patent for removing the drum from the kettle and supporting it out of the same for the reception and discharge of clothes, it is journaled in the ends of two levers D, which are secured upon the squared ends of a shaft 80 E arranged in boxes at the front top edge of the body A. Such levers are extended beyond the shaft, as shown in Fig. 1 and spiral springs F are attached thereto and to the side of the body A. These springs are of 85 such tension that they will balance the drum when the same is empty. They therefore prevent the drum striking too hard when lowered to the normal position indicated in Fig. 3, and they assist materially in raising 90 the drum out of the kettle when the washing has been effected. I desire it to be understood that I do not restrict myself to this construction and arrangement of the springs and propose to employ any form or arrangement by which the same result may be accomplished. A crank G is applied detachably to one of the squared ends of the shaft E, and by depressing its free end, the levers D will swing the drum up to the position indicated in Fig. 4. The drum may be prevented from swinging too far by stops a⁴, on the sides of the body A with which stops the levers D come into contact when the drum is raised and the springs will prevent the 95 shorter arms of the levers D striking the stops too hard. In fact the springs are fully sufficient to support the drum in required position without other aid. When so held in the elevated position, the door C' of the 100 drum may be opened, as shown in Fig. 4, for discharge of clothing and upon rotating 105

the drum so as to carry the opening to the upper side; the drum may be filled again with the clothes to be boiled and washed.

Within the drum I provide some short transverse partitions H, which constitute clothes-carriers, that is to say which are adapted for contact with the clothes in the drum and to carry them around a part of a revolution so that they are successively taken from the bottom of the drum to the top and allowed to fall back into the water. These clothes-carriers may be constructed of perforated metal or other suitable material and provided with end flanges by which they are secured by rivets to the conical ends of the drum.

In order to prevent the clothes from coming in contact with the edges of the woven-wire periphery of the drum, the conical heads are provided with a circular indentation c³, see Fig. 5, such indentation being arranged as close to the periphery as practicable. The conical ends of the drum are secured by bolts arranged outside the annular indentation c³.

The door C' of the drum is provided at its free end with a cross bar—see Fig. 6—whose end portions c⁴, are bent and project inward and are slightly curved outward at their extremities for automatic engagement with spring catches c³ secured to the ends of the drum.

Each of the cranks before described will in practice be detached when the other is being used. That is to say, preliminary to rotating the clothes drum C in the kettle B, the crank G of the shaft on which the arms D are journaled will be detached.

By the above described construction and

arrangement of the cover and the means for supporting the clothes-drum I have greatly simplified and reduced size, cost, and weight of the original machine and at the same time increased its efficiency.

What I claim is:—

1. The improved washing-machine, comprising a hollow body provided with an open boiler at its upper portion, levers pivoted to the top of the body near one side thereof and having short arms extending from the pivots a reticulated drum journaled in the long arms of the levers, springs attached to the said body and connected with the short arms of the said levers, the springs being under constant tension whereby they tend to raise the drum and resist its extreme or final movement in opening and closing, the stops a⁴ applied to the body in the position indicated, whereby the shorter arms of the levers are adapted for contact therewith when the drum is thrown upward and outward, as shown and described.

2. The improved washing-machine, comprising a hollow body, a boiler supported therein, a reticulated drum, levers pivoted on the body and the drum being journaled between their free ends, a cover which is hinged at one side contiguous to the pivots of the levers and adapted to be thrown over to horizontal position in which it is self-supporting, and the drum being adapted to swing upward and outwardly over the cover, substantially as described.

JOHN W. SEIFERT.
